OVERLOAD PROTECTION FOR DRIVE
MOTORS OF AUTOMATIC WASHING
MACHINES AND THE LIKEJoseph C. Worst, Bridgeport, Conn., assignor to
General Electric Company, a corporation of
New York

Application July 1, 1949, Serial No. 102,554

2 Claims. (Cl. 192—.02)

1
This invention relates to an improved control circuit and control device for the drive motor of automatic washing machines of the type in which clothes are washed and spin-dried in a single basket; and a particular objective of the invention is to provide means for automatically relieving the load on the drive motor and thus protecting its running winding against excess current resulting from an overload condition.

A popular make of automatic washing machine of the above-noted type uses a single drive motor to operate a washing device such as an agitator and to rotate the tub to extract the water from the tub and clothes by centrifugal action. By a conventional automatic program control switch the spin-dry period is initiated by the operation of an electrically operated valve which directs oil under pressure into a clutch shifting system to de-clutch the agitator mechanism and couple the motor to means constituting a direct drive between the motor and the rotatable mounting of the basket. The inertia of the loaded basket places a severe load on the motor as the spin begins, with the result that an undesirably large current may be drawn by the running winding of the motor. If this condition is permitted to exist for even a short time the motor winding may burn out.

I accomplish my above-stated principal objective of protection against such motor overload, as well as the further objectives of simplification of the protection agency and reduction of cost thereof, by providing a unique motor starting relay having an operating coil in series with the running winding of the motor and a biased armature system for closing the customary start winding circuit on the initial inrush of current to the motor and for controlling a switching device in series with the valve circuit. The armature bias is adjusted to relay coil strength so that if the loaded basket imposes too great a burden on the motor at the commencement of spin, the additional current drawn by the motor and the relay winding will deflect the armature sufficiently to open the valve circuit for reduction of the hydraulic pressure at the clutching means. The clutch will slip, and the load on the motor drop proportionately; and as the current drawn by the motor winding and relay coil drops as the result of the lessened load, the biased armature again conditions the valve circuit to valve the hydraulic pressure to the clutch assembly. The basket drive system will experience a succession of clutch engagements and partial de-engagements until the basket inertia has

been overcome and the motor load is at a normal level.

Other features and advantages will be apparent from the following description taken in connection with the accompanying drawing in which Fig. 1 is a representation of the motor and hydraulic clutch system of a conventional automatic washing machine and a somewhat schematic wiring diagram for the relay incorporating the present invention; and Figs. 2 and 3 are respectively a top plan view and a side elevation of a relay embodying the invention.

Referring now to Fig. 1, a washing mechanism 1 includes a motor in which stator 2 is suitably fixed within a housing 3 secured to a main frame structure 4. The stator is provided with a conventional start winding 5 and running winding 6. The rotor 7 has a tubular shaft 8 suitably journaled in a bearing 9. Rotatably mounted within the tubular shaft 8 is a shaft 10, to which is suitably affixed a clutch member 11 for cooperation with a complementary clutch element 12 affixed to the rotor. Also affixed to the rotor is a cup 14, to the lower flange of which is secured the end of a flexible metallic bellows 15. The opposite end of said bellows is fixed to a spin clutch member 16 which is suitably secured to a sleeve 17 rotatable on shaft 10. A spring 18 within cup 14 bears against a cap 19 suitably supported on shaft 10 and thus biases the bellows 15 toward collapse. Drive pinion 20 meshes with a gear 21 of a gear system carried by a frame 22. The gear frame 22 is suitably rotatably carried in a bearing 23 formed in the frame structure 4 and journaling a hub 24 extending from the frame. The main frame member 4 provides an anchorage for a brake element 25 arranged for cooperation with a combined brake and clutch element 26 having a driving connection with the hub by the ears 27 which fit slidably but closely within slots 28 formed in the flange of a cup member 30 fixed to said hub as shown. A spring 31 confined within cup 30 and pressing against a central web of the clutch member 26 urges the said member downwardly of Fig. 1 so that it engages the brake 25.

Hub 24 is concentric with a shaft (not shown) fixed to and extending from frame 22, and by means of which the wash basket (not shown) is spun. The gearing within the frame is such that with the frame 22 held against rotation an agitator (not shown) oscillates within the basket to effect washing of the clothes.

The bearing 9 has at its base an eccentric pump chamber within which operate the blades 32

which are slidably carried within the end of the tubular rotor shaft 8. Said blades comprise the impellers of a vane pump directly driven by the motor, said pump drawing oil from a sump 33 through an intake tube 34 and discharging it through an orifice 35 provided in a plate 36 forming the base of the pump chamber and through a passage 37 for distribution of lubricating oil under pressure. Affixed to the cover plate 36 is a dished cap 38 having an orifice 39 which forms the seat for an electrically operated valve, which most conveniently comprises a magnetic plunger valve 40 within the solenoid coil 41.

The foregoing structure is essentially shown and explained in greater detail in the presently pending application Serial No. 551,096, filed August 25, 1944, by Thomas T. Woodson, for "Clutch Structure for Automatic Washing Machine," and assigned to the assignee of the present application. For the present it will be sufficient to note that during the washing established by the operation of a suitable program switch (not shown) the motor is energized and the solenoid coil 41 de-energized to the Fig. 1 position, whereby the greater part of the oil pressure generated by the vane pump recirculates to the sump through an aperture 35 in cover plate 36, aperture 39 in cap plate 38 and along the sides of the polygonal plunger valve 40. A lesser quantity of oil under light pressure circulates through the system for lubrication, and a portion thereof passes upwardly through the apertures 42 and 43 to flow along the side wall of the shaft 10 and enter the space 44 between the respective clutch elements 11 and 12 from which it seeps through the openings 45 in clutch member 11 and 46 in the cap 14 to fill the interior of the bellows 15. Venting of the bellows 15 is provided by the bearing clearance between shaft 10 and sleeve 17. Under such condition of operation the spring 31 biases the element 26 against brake 25 and the shaft 10 and its thereon carried pinion 20 is connected to the rotor by the clutch members 11, 12. The gear frame being held against rotation by the brake, the agitator is oscillated to effect the washing operation. When the basket is to be spun for removal of water from the clothes, the program switch operates to energize the solenoid coil 41 to draw the plunger valve 40 upwardly to close the plate opening 39 and prevent the recirculation of oil to the sump 33. Under these conditions oil under substantial pressure flows into the chamber 44 faster than it can be bled out through the openings 45, and the clutch member 11 is lifted to disengage the clutch plate 12. The drive pinion 20 is then no longer powered. Oil pressure building up within the bellows 15 expands it to drive the clutch element 16 upwardly into contact with the clutch element 26. Additional bellows expansion raises the clutch element from the brake 25 and there is then a direct drive connection between the rotor and the drive cup 30 which, it will be recalled, is fixed to the hub 24 of the gear frame. The gear frame and thereby driven wash basket is thus arranged to be driven at motor speed.

It should be mentioned that the basket itself is purposely heavy for flywheel effect and with the water and laundry content, the total weight may be of the order of two hundred pounds. Accordingly, there is a very substantial inertia which must be overcome before the basket can be brought to motor speed and the motor is subjected to severe load conditions during the early stages of spin. Mechanical devices have been proposed

and used adjustably to bleed the bellows 15 according to the speed or torque of the motor and thus permit the same to collapse and withdraw the clutch member 16 partially from the combined clutch and brake member 26, so as to cause clutch slip and reduce the motor load.

The present invention utilizes the power demand of the motor, as represented by the amperage of the running winding 6, for controlling the electrically actuated valve 40 and thereby establishing direct control over the pressure of oil within the bellows 15. De-energization of the solenoid will cause the valve 40 to open the port 39 for recirculation of the oil to the sump, immediately reducing the bellows pressure.

My combined starting relay and valve control 50, see Figs. 2 and 3, utilizes a conventional coil 51 in series in the running winding circuit as appears from Fig. 1. The coil has a magnetic core 52 which advantageously comprises an end of a bracket 53 supported on the insulating base 54. The bracket also provides a bus bar for connection of the coil, and accordingly one end of the coil is brazed to the bracket, to which also is brazed the lead conductor 55. Armature 56 is carried on a leaf spring 57 and is biased by said spring and the flexure-adjustment screw 58 to move away from the core; in the illustrated embodiment, such movement is outward relative to the base. Fixed to the armature is a downwardly extending spring contact having a silver or equivalent contact 60 cooperating with a similar contact 61 resiliently carried by the base. A contact button 62 fixed directly to armature 56 cooperates with a contact 63 provided on an arm 64 carried by base 54 and projecting therefrom. The armature bias brings contacts 62, 63 normally to circuit closing position. Contacts 62 and 63 are the overload protection contacts, as later appears, and will open and close frequently under usual conditions. Accordingly, it is preferred that they be of tungsten.

As shown in Fig. 1, contacts 60, 61 are in the start winding circuit, and initial inrush of current to the running winding energizes coil 51 sufficiently to draw armature 56 to the core, as a result of which the start contact system 60, 61 will be closed and the circuit to the start winding completed. As the motor comes up to operational speed the current drawn by the running winding and the coil 51 decreases, so that the magnetism of core 52 is insufficient to hold armature 56 against its inherent bias to open contacts 60, 61 and to close contacts 62, 63. The motor thus continues operation on its running winding. Contacts 62, 63 are in the electrical valve circuit, and are in series with a switch 65, diagrammatically shown, but representing the spin-dry switch of the program switch. Until the program switch closes switch 65, the solenoid 41 remains de-energized even though contacts 62, 63 are closed. When the program switch comes into spin operation, however, switch 65 is closed by suitable means to energize the solenoid whereupon oil under pressure is valved into the bellows 15 with the aforementioned results.

If because of the inertia of the basket the motor load increases undesirably the running winding will draw excessive current and the relay coil 51 will attract the armature 56. However, the relationship of the contact systems is such that before the start contact system 60, 61 has closed, the spin valve contacts 62, 63 will be opened to de-energize the coil 41 and immediately relieve the pressure within the bellows 15 to slip the spin clutch system and thereby relieve the motor. The

motor will speed up and its running winding current decrease until the return of the armature 56 to the Fig. 1 position again closes the spin solenoid circuit to re-introduce suitable hydraulic pressure into the spin clutch system. In this fashion the hydraulic pressure in the spin clutch system is substantially directly responsive to the current drawn by the running winding of the motor, and the motor load is thus automatically decreased as the running winding current increases to a level beyond a normal or "safe" operating range. After a number of such operations depending on the inertia factors of the basket, the motor will bring the basket up to operating speed and operation will proceed normally through the spin cycle under satisfactory motor load conditions.

As a typical example of operating ranges, the armature bias on a device which I have constructed and tested under usual operating conditions will cause the contacts 62 and 63 to close when the running winding draws twelve amperes, but will release these contacts, without closing the start winding contacts at about fourteen amperes. The load relief resulting from the operation of the electric valve is quickly effective and under normal wash loads, the clutch slippage returns the running winding current almost immediately to the twelve ampere level at which the electric valve again becomes energized.

While I have shown a particular embodiment of my invention, it will be understood, of course, that I do not wish to be limited thereto since many modifications may be made; and I therefore contemplate by the appended claims to cover any such modifications as fall within the true spirit and scope of my invention.

What I claim as new and desire to secure by Letters Patent of the United States is:

1. In a washing machine of the single basket wash and spin-dry type having a single motor for the washing and spin-drying operations, said motor having a start winding and a running winding, a hydraulically actuated clutch system for drivingly connecting the motor to the basket, a source of hydraulic pressure, and an electrically operated valve for valving liquid under pressure to said clutch system to engage the clutch or for relieving said pressure to permit said clutch to disengage according to whether the valve circuit is closed or open, the improvement in means for relieving said pressure in the event of motor overload comprising a relay switch having an actuating coil in series with said running winding, a switch in the start winding circuit, and armature means common to said switches for closing or opening one or the other according

to the condition of energization of said coil, said armature being biased to close said valve circuit but responsive to the value of the starting current demand in said motor to open said circuit and close the start winding circuit, and under current demand conditions above normal running values but less than the starting value to open the valve circuit switch for clutch pressure relief without closing said start winding circuit switch.

5 2. In a washing machine of the single basket wash and spin-dry type having a single motor for the washing and spin-drying operations, said motor having a start winding and a running winding, a fluid pressure actuated clutch system for drivingly connecting the motor to the basket, a system for generating fluid pressure and conducting the same to said clutch, said system including normally open valve means and electrically responsive means effective when energized to operate said valve to direct liquid under pressure to said clutch to engage the same and when deenergized permitting said valve to open for release of said clutch-engaging pressure, and an electric circuit for said valve operator, the

to the condition of energization of said coil, said armature being biased to close said valve circuit but responsive to the value of the starting current demand in said motor to open said circuit and close the start winding circuit, and under current demand conditions above normal running values but less than the starting value to open the valve circuit switch for clutch pressure relief without closing said start winding circuit switch.

10 2. In a washing machine of the single basket wash and spin-dry type having a single motor for the washing and spin-drying operations, said motor having a start winding and a running winding, a fluid pressure actuated clutch system for drivingly connecting the motor to the basket, a system for generating fluid pressure and conducting the same to said clutch, said system including normally open valve means and electrically responsive means effective when energized to operate said valve to direct liquid under pressure to said clutch to engage the same and when deenergized permitting said valve to open for release of said clutch-engaging pressure, and an electric circuit for said valve operator, the improvement comprising a single pole, double throw switch having one throw position serially connected in said valve operator circuit and the other throw position in said start winding circuit, means biasing said switch into valve circuit closing position, and electromagnetic means in series with the motor running winding for operating said switch in accordance with the magnitude of the current drawn by said winding, said electromagnetic means being so related to the switch biasing means that current drawn by the winding under normal or lightly overloaded motor demand will energize said electromagnetic means insufficiently to overcome the switch bias, moderate overload current demand will overcome said bias sufficiently to open said valve circuit without completing said start winding circuit, and the current drawn by the winding under severe motor overload will throw said switch to complete said start winding circuit after opening said valve circuit.
